UNITED STATES PATENT OFFICE.

WILLIAM T. GAINES, OF NEWCASTLE, KENTUCKY.

WIRE-FENCE MACHINE.

SPECIFICATION forming part of Letters Patent No. 723,262, dated March 24, 1903.

Application filed December 28, 1901. Serial No. 87,582. (No model.)

To all whom it may concern:

Be it known that I, WILLIAM T. GAINES, a citizen of the United States, residing at Newcastle, in the county of Henry and State of Kentucky, have invented a new and useful Wire-Fence Machine, of which the following is a specification.

This invention is an improved wire stretcher and carrier, and relates particularly to a device for use in constructing fences, and has for its object to provide a simple and economical arrangement for carrying a roll of wire in such position that the strands may be conveniently secured to the posts.

Another object of my invention is to provide an arrangement for collecting loose or "down" wire of a fence, so that the wire may be conveniently used in the reconstruction of a fence; and with these objects in view my invention consists in certain details of construction and novelties of combination and arrangement of parts, as will be fully described in the following specification and pointed out in the claims, reference being had to the drawings, in which—

Figure 1 is a plan view of my improvement as arranged upon the front gear of a wagon. Fig. 2 is a side view of the same, the near wheel of the wagon-gear being removed; and Fig. 3 is a detail perspective view of the frame and reel detached.

My invention is arranged and constructed particularly to be used in connection with the front running-gear of a wagon, by which the device is supported and transported from place to place and along the route of the fence.

By referring to the drawings it will be seen that I employ the front running-gear A of a wagon, to which is connected a rearwardly-extending bar B, that may be the ordinary reach-bar or any suitable form of bar, upon which is mounted a frame C, consisting of the side members C', whose forward ends are suitably connected to a perforated cross-bar C², and an intermediate cross-bar C³, through which passes a bolt C⁴, that pivotally connects the frame upon the bar, and by providing the front perforated bar the frame may be turned either way for the purpose, as will appear later on.

In the rear ends of the side members C' is mounted a shaft D, upon which is held a reel E for carrying the wire. One end of the shaft D is provided with a crank-handle F, and on the opposite end is placed a sprocket G, that is connected by means of a chain-belt I to a sprocket-wheel H, secured upon the hub of one of the wheels of the running-gear.

The side members of the frame are provided with brackets J, in which is held a brake-bar K, that is connected to a lever L, carried by the frame through the medium of a link-bar L'. The said lever L also carries a pawl L², that engages a ratchet-section of the frame for holding the bar tightly against the reel when it is braked.

The bar B is suitably braced to the running-gear A by means of a chain M, and in practice I also prefer to provide the said running-gear with a brake or chock bar N to limit or prevent any rearward movement of the running-gear during the construction of a fence. In practice the bar N is pivoted to the axle-frame of the running-gear and trails upon the ground; but should it be desired to elevate the bar and hold it in such position so the device may be backed I provide the bar with a hook N', that engages a staple N², arranged upon the axle-bar.

From the foregoing it will be seen that when the device is arranged as described the down wire may be easily and conveniently collected by simply fastening one end to the reel and driving the device over the ground upon which the wire lies; but in the construction of a fence the chain I is removed, when by propelling the device the wire is automatically unwound from the reel and secured to the posts of the fence, the movement of the reel being controlled by the brake-bar K, so that suitable tension may be applied to the wire, and by arranging the cross-bar C² the reel may be positioned upon the bar B at any angle to accommodate the distance the running-gear is traveling from the posts.

It will thus be seen that my improvement is exceedingly simple and can be applied to the running-gear of a wagon at a very small cost, and, further, by providing the crank-handle F upon the reel-shaft the reel may be

operated independently of the connection of the wheel of the running-gear, as occasion may sometimes require.

Having thus fully described my invention, 5 what I claim as new, and desire to secure by Letters Patent, is—

1. In a device of the kind described, the combination with the running-gear of a vehicle, a bar extending rearwardly thereof, a substantially rectangular frame horizontally pivoted to the rear of said bar its front member consisting of a perforated cross-piece, a reel pivoted to the rear of said frame between its side members, and means for automatically 15 actuating said reel.

2. In a device of the kind described, the combination with the running-gear of a wagon, of a bar extending rearwardly thereof, a frame pivoted to the rear of said bar, said frame 20 comprising forward-converging side members, a cross-bar connected to the forward ends of the side members and having a plurality of apertures therein, a cross-bar connecting the side members intermediate their 25 ends and having an aperture formed midway its length, brackets secured on said side members, a brake-bar held in said brackets, a reel mounted to the rear of the frame, means for actuating the brake-bar and means for 30 rotating the reel.

3. The combination of a reel-supporting frame, comprising the side members and the cross members, a shaft carrying a reel journaled upon the frame and having one end 35 thereof provided with a crank-handle, guides secured upon the frame and having a bar operating therein, a lever pivoted upon the frame, a link connecting the said bar and lever, a pawl arranged upon the lever and a 40 ratchet-section arranged upon the frame, substantially as shown and described.

4. In a device of the kind described, the combination of the running-gear of a wagon, a bar extending rearwardly therefrom, a frame 45 pivotally held upon the outer end of the said bar, a reel journaled in the said frame, the shaft of said reel having a sprocket arranged upon one end thereof, a brake-bar carried by the frame, a lever pivotally held upon the

frame, a link connecting the said bar and lever, a sprocket arranged upon the wagon-gear, a chain connecting the said sprocket of the reel-shaft and the sprocket of the wagon-gear, and means connecting the said frame and bar whereby the said frame may be adjustably held to the bar, substantially as shown and described.

5. In a device of the kind described, the combination of a wagon-gear having a bar extending rearwardly therefrom, a chain connecting the said bar and gear, a frame pivotally held upon the end of the said bar, said frame comprising side members and the front perforated cross-bar, and an intermediate bar, a shaft mounted upon the said side bars 65 and having a reel mounted thereon, guides formed upon the said side members, a brake-bar operating in the said guides, a lever pivotally held to one of the said side members and carrying a link that is connected to the said 70 bar, ratchet-teeth formed upon one of the side members adjacent the lever, a pawl carried by the lever and adapted for engagement with the ratchet-teeth, and a pin connecting the said cross-bar of the frame, with the rearwardly-extending bar of the wagon-gear, and means for operating the said reel, substantially as shown and described.

6. In a device of the kind described, the combination of the wagon-gear having a bar 80 extending rearwardly therefrom, a frame pivotally held upon the rear end of the bar, the said frame having a perforated cross-bar formed integral therewith by which the said frame may be held at various angles to the 85 longitudinal line of the said rearwardly-extending bar, a reel carried by the said frame, a brake-bar carried by the frame and arranged for engagement with the reel, and means for operating the said reel, and means 90 for operating the said brake-bar, and a chock carried by the said running-gear, substantially as and for the purpose specified.

WILLIAM T. GAINES.
